UNITED STATES PATENT OFFICE

ALBERT C. SCHICKLER, OF CLEVELAND, OHIO, ASSIGNOR TO EDMUND E. ALLYNE, OF CLEVELAND, OHIO

REFRIGERATING SYSTEM

Application filed October 27, 1926. Serial No. 144,461.

This invention relates to refrigeration, and more particularly to refrigerating systems of the absorption type, where a suitable refrigerant, such as ammonia, is intermittently distilled from a suitable absorbing agent, such as water, and is condensed and collected in an evaporator during the first half of the cycle, and then during the second half of the cycle, is evaporated in the evaporator to produce the refrigerating effect, being returned to and distributed in the absorbing agent in the boiler, now functioning as an absorber.

The invention has for its object to provide an efficient refrigerating system which may be effectively sealed and which avoids any necessity of valves or stuffing boxes, with the possible leaks or loss of pressure and efficiency, or internal working parts which get out of order and interfere with proper operation.

A further object is to provide a system of this kind with a very efficient boiler in which heat is produced by applying electrical energy directly to the liquid in the boiler, with immediate heating effect, thereby reducing the heating period and avoiding loss of energy.

A further object is to provide an improved electric heater in which heat is produced by the resistance to current flow of the liquid absorbing agent, together with improvements in the arrangement of the electrodes, their levels for safety purposes, their mounting and insulation from each other, and their provision with means for inducing circulation of the boiler liquor.

A further object is to provide a system which returns to the still-absorber all absorbing agent carried to other parts of the apparatus, such as to the evaporator, either entrained in the gaseous refrigerant during distillation or carried to the evaporator by a "boil over", such as sometimes occurs in absorption systems, and an arrangement for this purpose which compels the distilled gaseous refrigerant to follow its customary path for condensation and collection in the evaporator and for return to the absorber, but which supplies a separate gravity return path from the evaporator to the boiler for absorbing agent, such as water, or for the heavier aqua-

ammonia, but which also prevents any flow of the gas or liquid through the latter path from the boiler to the evaporator.

A further object is to provide an absorption refrigerating system embodying an evaporator located at a higher level than the boiler and a free gravity return path for heavier liquid from the evaporator to the boiler, but in which path suitable means, such as a hydrostatic seal, prevents return of other than the heavier liquor, the presence of which in the evaporator is undesirable, and also prevents gas or liquid flow from the boiler to the evaporator except through proper channels.

A further object is to provide an improved liquid or hydrostatic seal in which the sealing liquid has a density greater than water or anhydrous ammonia and is trapped in a U-tube of special form, enabling application of the opposite ends of the liquid in said tube of columns of aqua-ammonia or ammonia, as the case may be, and yet in which the sealing liquid is trapped in the U-tube against possible escape, such as by physical inversion of the apparatus, which might occur during shipping or prior to installation.

Still another object is to provide an automatic control system, including means for shifting from the heating to the refrigerating period of the cycle and back again, at the proper times, and particularly such a means controlled by or in accordance with the level of liquid in one of the containing vessels therefor, such as the boiler, compelling heating and distillation at one time and equally cutting off the heat and starting refrigeration at another time.

A further object is the organization in or with such an automatic control system of a thermo-siphon cooling system for the boiler, or, in other words, one in which a mass of cooling liquid, such as water, is permitted to circulate or is trapped without circulation according to the desirability of cooling the boiler during absorption or of preventing the abstraction of heat therefrom during boiling.

Further objects of the invention are in part obvious and in part will appear more in detail hereinafter.

In the drawings, which represent one suitable embodiment of the invention, Fig. 1 is a rear elevation, partly broken out, of a refrigerator embodying the apparatus and particularly illustrating the piping system, most of the electrical control features being omitted for simplicity of illustration; Fig. 2 is a simplified diagram of the circulation system, prepared for convenience in explanation; Figs. 3, 4 and 5 are detail sectional views, on a larger scale, illustrating the U-tube and liquid seal in various positions to which it may be turned by inversion of the entire apparatus; Fig. 6 is a detail longitudinal section through the boiler; Fig. 7 is a detail sectional elevation, on a larger scale, on the line 7—7, Fig. 6, and illustrating the heating elements; and Fig. 8 is a diagrammatic view illustrating the electric control system.

Referring to Fig. 1 the apparatus forming the subject matter of the present invention is applied to a household refrigerator, including a casing or jacket 1 resting on the floor and provided with a horizontal cross wall 2 forming the floor of the insulated refrigerating chamber 3 and the roof of a non-insulated chamber or space 4 within which most of the working parts are contained, a convenient arrangement because it avoids stooping to manipulate the materials in the refrigerating chamber and stores the working parts in space of less value for refrigerating purposes. In the lower space 4 is located a relatively large tank 5 adapted to receive a mass of suitable cooling liquid, such as water, any heat in said tank readily radiating through its walls to the atmosphere. The bottom portion of the space 4 contains the boiler 6 and above it a small sealed receiver 7.

As shown in Fig. 6, boiler 6 is of generally cylindrical or drum form, being completely sealed against the atmosphere and being provided with a suitable water jacket, such as the sheet metal enclosure or envelope 8, spaced by the knobs or heads 8a and welded in place at one end and communicating at a high point by the pipe 9 and valve 10 with the upper portion of the cooling tank 5, and also communicating at a low point by the pipe 11 with a low point in the cooling tank. The chamber within the boiler 6 contains the electric heating elements, later to be described, and the gas space in the boiler communicates by an inverted U-pipe 12 with the receiver 7, the end of the pipe 12 opening at a low level in said receiver. Drainage or return from the receiver to the boiler is provided by the pipe 13, of ample cross sectional area, the upper end of which extends up through the bottom of the receiver and terminates therein at a level above the bottom of pipe 12, and the lower end of which pipe 13 may have one or more perforated branches 13a for distribution throughout the absorbing agent of the gas returned for absorption therein.

From the top of the receiver 7 extends a pipe 14, the first portion of which is of relatively large size and is inclined upwardly and may be bent back and forth, as shown, to form a rectifier, in which a large proportion, if not all, of the water entrained in the gaseous refrigerant may collect and from which it drains back into the receiver 7 and thence into the boiler. However, such rectifiers are usually exposed to the outside air, which may be cool, and therefore many condense some ammonia which is returned to the boiler without the production of a useful refrigerating effect. Because the present system provides an efficient means and method of unimpeded return to the boiler of practically all absorbing agent carried over to the evaporator, it is not so important to rectify the distilled gas, but the entrained absorbing agent or the effects of a "boil over" may be taken care of even if it reaches the evaporator. Therefore, a large proportion of the pipe coils of the rectifier may be omitted and the gas may be led directly from the top of the receiver 7 through one pass of pipe 14 to the condenser 16, as shown in Fig. 2.

The condenser consists of coils or convolutions of pipe of small size located at any suitable level and, as shown, being located in the cooling liquid in the tank 5, the distilled gas being supplied to the upper convolutions of the condenser and the condensed refrigerant flowing to the bottom, from which the pipe 17, also of small size, leads to the top of the evaporator 18, which is shown as of simple drum form, but which may be of any suitable shape or configuration. To increase efficiency the condenser pipe may be provided with heat radiating means, such as a series of washer-like fins 16a distributed at intervals along its length.

The apparatus so far described is in one sense a simple absorption type refrigerating system. The receiver 7, U-tube 12 and pipe 13 function according to Willsie Patent No. 1,186,463, granted June 6, 1916, to compel the gas distilled in the boiler to travel through the pipe 12 to the receiver and thence through pipe 14 to the condenser, but during the refrigerating period compel the gas returning through pipe 14 to enter the boiler through pipe 13 and bubble up through the absorbing agent to be absorbed thereby. Pipe 13 is purposely made of large cross sectional area to avoid choking said pipe, such as by the sudden discharge from pipe 14 of a collection of drops of liquid, a choking which might permit the level of liquid in the receiver to rise high enough to cause some liquid to be forced over into pipe 14 and surge into the condenser, or in other words to start a "boil over". The large size of pipe 13 also provides a copious and quick path for the gas returning to the boiler.

In the present apparatus the return of the

heavier absorbent bearing liquor from the evaporator to the boiler occurs through a pipe 19, communicating with the bottom of the evaporator and leading to one leg or chamber of the two communicating chambers of a hydrostatic seal of generally U-form, marked 20, the other leg or chamber of which communicates by pipe 25 with the bottom of receiver 7. The hydrostatic sealing device contains a quantity of sealing liquid 21, more dense than the absorbing agent or refrigerant, such as water and ammonia, and which in quantity must be definite, with due regard to the size and configuration of the U-tube walls and to the column of liquid in the pipe 19. It must also be a substance which is not affected by the absorbing agent, such as water, or by the refrigerant, such as ammonia, or in the present instance, by any reagent which may be added to the liquid to prevent the production of inert or useless gas, such a reagent, for example, being sodium bichromate. One suitable sealing liquid for use with water, ammonia and sodium bichromate is metallic mercury. The amount of mercury must be such that when all of it is moved toward the still and into one leg of the U-tube, or to such position that water or ammonia can pass the bottom of the U-tube, then the effective height of the maximum mercury column is of greater value than and will overbalance a column of anhydrous ammonia filling pipe 19 to the top of the liquid in the evaporator, but is of less value than and will be overbalanced by a column of water or aqua-ammonia in the pipe 19 to the same level. Since the density of mercury is about 13.6 and ammonia solutions have a density of about .8, it is clear that if the evaporator, which must always be higher than the boiler, is 40 inches above the boiler, the maximum mercury column must be approximately 2½ inches high.

Referring now to the diagram in Fig. 2, the apparatus, and more particularly the mercury seal, operates as follows:

As a general rule the level of liquid in receiver 7 is at the top of the pipe 13. During the boiling operation the distilled gas passes over to receiver 7 and thence to the condenser, with a rise in pressure throughout the apparatus. Let us assume that prior to the first operation after installation of the apparatus no liquid whatever has been conveyed to the evaporator, but that the latter as well as the pipe 19 are filled only with ammonia gas. The rising pressure is effective on both legs of the mercury in the U-tube 20. Moreover, the column of liquid in receiver 7 is not sufficient to fully depress its leg of the U-tube, so that no liquid or gas can flow past the U-tube from receiver 7 to the pipe 19, but distillation goes on with supply of gas to the condenser until the liquid collected therein is lifted by the increasing pressure and is discharged into the top of the evaporator, from which, of course, it flows downwardly through pipe 19 to be supported on its mercury leg. The arrangement, it has been said, is such that the maximum mercury column will support the full liquid column in pipe 19 if said column is of approximately anhydrous ammonia, but will not support the full column if it is of heavier, absorbent bearing liquor or aqua-ammonia. Consequently, ammonia and water delivered to the evaporator are collected by the pipe 19, the heavier liquor or water collecting at the bottom until the weight of the liquid column, by additions of heavier liquor or aqua-ammonia, overbalances the maximum mercury leg, whereupon some of the heavier liquor at the mercury leg flows back and enters the bottom of the receiver 7 and drains to the boiler. The net effect is to establish and maintain in pipe 19 a level of contact between the heavier aqua-ammonia and approximately anhydrous ammonia, which level is maintained substantially uniform throughout all conditions of the apparatus. In case of a "boil over" it is obvious that no matter how great the quantity of aqua-ammonia delivered to the evaporator it promptly gravitates back through pipe 19 and past the mercury seal to the boiler until normal conditions are again established.

As indicated in Figs. 3, 4 and 5, the mercury seal or U-tube is of special form. While the cavities and channels therein are the essential thing and may be cored out or formed in any suitable material unaffected by mercury, such as cast iron, yet in practice it may be made of a section of tubing 22 bent to U form, the ends thereof being enlarged to form wells 23 closed at their upper ends by walls 24 through which the ends of the pipe members 25, 19 extend. The ends of said pipes extend into the wells to about their centers, where they are suitably baffled, such as by being closed by end walls or caps 27, one or a number of small holes 28 being provided in the side walls of the pipes through which the absorbing agent may flow. The wells 23 are made of such size that even if the entire refrigerating apparatus, including the U-tube, is turned on one side, as in Fig. 4, or is even completely inverted as in Fig. 5, the upper surface 21a of the mercury, even if all of the same is collected in one well, will be below and out of contact with the openings 28. By baffling the ends of the pipes with the caps 27, and by providing wells of sufficient size, as described, it is practically impossible for any of the sealing agent, such as mercury, to escape under any conditions.

The boiler heater, in the present apparatus, is of special form. It comprises two conducting elements insulated from each other but relatively closely spaced, the A. C. current conducted to them being caused to flow

across the gap and by overcoming the resistance of the liquid to heat the same. These electrodes are preferably arranged in a manner to promote liquid circulation during the heating operation. As indicated in Figs. 6 and 7 one of the electrodes 29 is of hollow tubular form with its axis vertical, being welded or otherwise permanently located within the boiler and thereby establishing conductive relation with its shell. Suitable openings or recesses are provided near the bottom of electrode 29 to insure free communication and flow of liquid from the outside to the inside of the electrode at its bottom. If the boiler is of cylindrical form and electrode 29 is also of cylindrical form with its bottom cut off square, as in Fig. 7, it can be perched in the boiler and welded at two opposite points, as at 29a, so as to leave gaps between its lower edge and the boiler wall, but additional recesses 30 may be provided if desired.

Within the upper end of electrode 29 is mounted the cooperating electrode 31, which is of disc form in plan view and which is coaxial with the tube 29 and is properly sized and spaced according to the desired heating effect. As shown, said electrode 31 is mounted fast upon an insulating porcelain tube 32 sleeved upon a bolt 32a extending through aligned openings in member 29, a pair of insulating spacers 33 separating the electrodes from each other.

With this arrangement, by connecting electrode 31 to one side and electrode 29 or the shell of the boiler to the other side of an A. C. electric circuit with proper power rating, current flows across the gap between the two electrodes so long as they are sufficiently immersed in the absorbing agent, the current effect heating the liquid and causing it to rise within the tube 29 and flow over the upper edge thereof, being replaced by additional liquid flowing into the tube 29 through recesses 29b and 30. In the practical operation of this system the quantity of liquid is preferably so chosen that in ordinary operation its upper surface never drops below the level of the top of tube 29, so that rapid circulation always occurs with a uniform heating effect when the heater is in operation.

However, one of the electrodes, such as electrode 31, is placed at a level above the bottom of the boiler and particularly at such a level that in case the control circuits or devices fail to work or operate incorrectly, or in case for any reason the heating current is continued indefinitely, the level of liquid finally drops below said electrode 31, automatically interrupting or opening the heating circuit. The level of electrode 31 is such that this occurs before the pressure and temperature of the boiler rise to any unsafe degree. The boiler is therefore automatically

safeguarded against dangerous conditions from overheating.

Fig. 8 illustrates diagrammatically the control circuits and devices, which include two switch members 35, 36 mounted to rock simultaneously upon an axis indicated at 37, such as by being mounted in a suitable rocking frame having an operating member, such as the arm 38, connected for operation to the core 38a of an electro-magnet. Switches 35 and 36 may be of any suitable form answering to the requirements, although they are shown as of the mercury form, including a chambered insulating casing, such as of glass, preferably evacuated and containing a small mass of mercury adapted to close the circuit through one or more pairs of contacts, as will appear. Switch 35 has two such pairs of contacts marked respectively 39, 40, while switch 36 has a single pair of contacts 42. The last named contacts 42 are in a circuit from L1 by way of wire 43 to the electrode 31. Insulated connection to said electrode through the wall of the boiler may be secured by using a device 34 similar to a spark plug, to the outer end of the conducting member of which the lead wire is secured, and the inner end of which is cupped to make contact with a resilient wire 44 fastened to electrode 31.

Contacts 39 are in a circuit from L1 by way of wire 45 to said contacts, thence through a coil 46 and wire 47 to a short terminal 48 passing through the porcelain center of another special spark plug. Contacts 40 are in another circuit from L1 including wire 49, said contacts, a coil 50, and wire 51 to a long terminal 52 passing through the porcelain center of the same spark plug. The metal shell of said spark plug, which is screwed into a fitting in the wall of the boiler, has short and long terminals 53, 54 within the boiler. The several terminals of this spark plug are in pairs, terminals 48 and 53 being short and terminating at the desired upper level A of liquid in the boiler. Terminals 52 and 54 are longer and terminate at the desired low level of liquid in the boiler, a level just above the top of the tube 29, as indicated by the line B. The shell of the boiler is grounded to L2 by wire 55.

Suitable connections are also provided for actuation of the thermo-siphon valve 10, the operating handle 61 of which is connected by the rod 56 to the core 57 of a solenoid including two coils 58, 59. Movable with the core is an insulating block 60 carrying a resilient contact blade 62 adapted in the two positions of the core to engage relatively stationary contacts 63, 64. A flexible lead from the wire 65 connects the blade 62 to L2 and the two coils 58 and 59 are respectively in branch circuits 66, 67, one from the contacts 39 to contact 64 and the other from the contacts 40 to the contact 63. The core 57 is

alternately moved back and forth to open and close the thermo-siphon valve by alternate energization of the two coils 58, 59, as will appear.

5 Fig. 8 illustrates the parts in that position when the system has just begun the refrigerating portion of its cycle. The level of liquid in the boiler 6 is low, the heat is cut off because the mercury in switch 36 is at the 10 opposite end of its tube from contacts 40 and the core 57 is in the full line position with the valve 10 open. The colder water at the bottom of the thermo-siphon tank therefore flows into the bottom of the water jacket 15 around the boiler, the warmer liquid in said jacket rising and flowing into the top of the thermo-siphon tank. This shot of colder liquid starts the absorbing operation and the, gas evaporated in the evaporator returns to 20 the boiler and is absorbed therein. At the beginning of the refrigerating operation, as will appear, the level of liquid has lowered to such a point that both of the terminals 52, 54 are out of contact with the liquid or are 25 immersed only very slightly, to such an extent that negligible current flows between them. During refrigeration the level of liquid in the boiler rises and almost immediately said terminals 52, 54 are immersed, 30 but no special effect follows because the contacts 40 are open. Finally the level of liquid rises to approximately the level A, Fig. 8, or, to a level at which the ends of the members 48, 53 are sufficiently immersed in the liquid 35 to conduct enough current from L1 to L2 to energize coil 46. A material immersion is necessary and actuation of the coil 46 will not be caused by mere drops of liquid which may chance to lodge on members 48, 53. However, when sufficient immersion occurs coil 40 45 is energized and elevates the core 38a to the position shown in dotted lines Fig. 8, thereby rocking the switch carrying frame and turning the switch tubes to their second 50 position. As they turn the mercury masses roll to the right hand ends of the switch tubes. That mercury in tube 35 closes a circuit across the contacts 40 as soon as it reaches them, with two effects. First, it energizes 55 coil 59 with a rush of current which slams over the core 57 to its dotted line position Fig. 8, thereby closing the thermo-siphon valve 10 and stopping further water circulation, and also breaking the circuit through coil 59 and closing a new circuit through coil 58. Core 39 is of course raised with a slam, due to the full current effect through coil 46, and rocking motion of the switch carrying 60 frame immediately opens the circuit through said coil at contacts 39. The second effect of closing the circuit at the contacts 40 is to energize coil 50 which remains effective as a holding coil to hold the frame in its new position until the termination of the boiling operation. The movement of switch 36 to

its second position closes the circuit through contacts 42 and supplies current for heating purposes, the liquid boiling and circulating in the boiler and the gas being driven over for condensation as described. The flow of current through coil 50 continues so long as members 52, 54 are materially immersed in the liquid, but when the level thereof drops to level B and sufficiently reduces the area of liquid contact and the conductivity between contacts 52, 54, said coil is de-energized and the rocking frame returns by gravity to its former position shown in Fig. 8, whereupon the circuit 66 through contacts 39 and coil 58 is completed, slamming over the core 57 to its full line position Fig. 8, opening the thermo-siphon valve, and resetting the circuit to coil 59 for the next operation.

The arrangement of the control circuits and devices for valve 10 is of especial importance because it always keeps the valve 10 in the proper position, open or closed, to be in step with the boiling and refrigerating operations, and is unaffected by accidental opening of the main line circuit for any reason or at any time.

To protect the system against any possible overheating of the boiler the latter may be provided with an external well 70 closed by an insulating member, such as a fiber disc 71, through which two leads of the circuit 43 extend to a fusible wire or link 72. As a result, if the temperature of the boiler rises beyond a dangerous maximum the link 72 fuses and cuts off the current supply to the heater.

As indicated in Fig. 1, the upper portion of the pipe 19, adjacent the evaporator, may be bent back and forth into one or more passes 73, lying in the same parallel plane and just beneath the evaporator, said passes being suitably supported if desired and thus serving as supports for one or more trays 74 designed for the freezing of ice cubes, as is customary. The approximate level of contact beneath the approximately anhydrous ammonia and the heavier aqua-ammonia or water is usually at a level below these passes 73, which thereby contain substantially anhydrous ammonia and function as a portion of the evaporator during the refrigerating operation. Freezing of the ice in the trays is rapid because the trays are located directly beneath the cold evaporator and are supported by refrigerating pipes. Also, the ice cubes are found not to melt so rapidly during the boiling period when the trays are located as shown.

What I claim is:

1. Absorption type refrigerating apparatus, comprising a still-absorber, a condenser, an evaporator, a drainage conduit from the bottom of the evaporator capable at all times of completely draining the evaporator, said conduit including communicating chamber

parts containing a liquid heavier than any of the liquids in said apparatus unaffected by any of the gases or liquids in said apparatus and arranged in two columns which permit free drainage from the evaporator of undesirably present absorbing agent but prevent drainage of useful refrigerant.

2. Absorption type refrigerating apparatus, comprising a still-absorber, a condenser, an evaporator, a drainage conduit from the bottom of the evaporator capable at all times of completely draining the evaporator, said conduit including communicating chamber parts containing mercury in two columns which permit free drainage from the evaporator of undesirably present absorbing agent but prevent drainage of useful refrigerant.

3. Absorption type refrigerating apparatus, comprising a still-absorber, a condenser, an evaporator, a drainage conduit from the bottom of the evaporator capable at all times of completely draining the evaporator, said conduit including communicating chamber parts containing mercury in two communicating columns which permit free drainage from the evaporator of undesirably present absorbing agent but prevent drainage of useful refrigerant, said chamber parts being provided with means preventing escape therefrom of the mercury upon change in position of the apparatus.

4. Absorption type refrigerating apparatus, comprising a still-absorber, a condenser, an evaporator, a drainage conduit from the bottom of the evaporator capable at all times of completely draining the evaporator, said conduit including communicating chamber parts containing mercury in two communicating columns which permit free drainage from the evaporator of undesirably present absorbing agent but prevent drainage of useful refrigerant, the chamber parts of the conduit being provided with wells trapped from the conduit ends to prevent escape of the mercury into said conduits when the apparatus is inverted.

5. A hydrostatic sealing device for refrigerating systems, comprising a U-tube containing sealing liquid, the legs of the U-tube being connected to circulating conduits, and means for preventing escape of the sealing liquid into said conduits upon inversion of the device.

6. A hydrostatic sealing device for refrigerating systems, comprising a casing provided with two chambers containing sealing liquid and communicating below the upper surface of the sealing liquid therein, the two chambers being connected to circulating conduits, and means for preventing escape of the sealing liquid into said conduits upon inversion of the device.

In testimony whereof I hereby affix my signature.

ALBERT C. SCHICKLER.
